HAT

Hymen Shrager and Barney Shinberg, Westerly,
R. I., assignors to American Felt Company,
Glenville, Conn., a corporation of Massachusetts

Application March 29, 1946, Serial No. 658,086

8 Claims. (Cl. 2—194)

1

This invention relates generally to the class of apparel and pertains particularly to improvements in hats.

A principal object of the present invention is to provide an improved construction in hats, particularly hats made of felt containing wool and other textile fibers, by the incorporation with the felt, fibers of a specific type of synthetic resin material whereby there is imparted to the hat, and particularly to the brim portion thereof, an additional flexibility and resiliency.

Another object of the invention is to provide an improved felt hat having a brim constructed in a novel manner by the inclusion therein of fibers of a specific type of synthetic resin material, whereby such brim is made relatively stiff, flexible and resilient and at the same time retains the very desirable woolly feel or, in other words, is free of any feeling of board-like stiffness.

A still further object of the invention is to provide an improved hat having a stratified brim wherein one of the layers contains synthetic resin fibers to give to the brim a desired increased stiffness, flexibility and resiliency, while the surfaces of the brim retain the natural woolly feel of a hat brim made solely of wool and other textile fibers commonly presently employed in the manufacture of felt hats.

A more specific object of the present invention is to provide an improved felt hat construction having synthetic resin fibers of a copolymer of vinyl chloride and vinyl acetate incorporated therein, either in the brim alone or in the brim and crown, but particularly in the brim thereof.

Other objects and advantages of the invention will become apparent as the description of the same proceeds and the invention will be best understood from a consideration of the following detailed description taken in connection with the accompanying drawing forming a part of the specification, with the understanding, however, that the invention is not confined to a strict conformity with the showing of the drawing but may be changed or modified so long as such changes or modifications mark no material departure from the salient features of the invention as expressed in the appended claims.

In the drawing:

Figure 1 is a cross section of a conventionally illustrated hat constructed in accordance with an embodiment of the present invention.

Figure 2 is a detail section on an enlarged scale of the brim and a portion of the crown illustrating the use of the resin fibers in both.

2

Figure 3 is a detail similar to Figure 2, but showing the use of the fibers in the brim only.

Figure 4 is a sectional detail of an embodiment in which the crown and brim are both stratified and a stratum of each contains the resin fibers.

In Figure 1 of the drawing there is conventionally illustrated a cross section of a felt hat of brim and crown construction, which is generally designated 10 and which comprises the crown portion 11 and the brim 12. It will be understood, of course, that the crown and brim portions have been illustrated disproportionately thick in order that the invention may be better illustrated and described and that in the manufacture of a felt hat in accordance with the present invention the brim and the crown will be of the usual standard thickness for the particular type of hat under construction.

The present invention is not limited in any manner as to the character of the material making up the felt employed, it being understood that such material may be made in any way and may be of any of the usual kinds used in connection with the manufacture of felt hats.

25 In carrying out the present invention the fibers of Vinyon, which is a copolymer of vinyl chloride and vinyl acetate, are combined in different proportions or quantities in the hat brim and/or crown, and the hat brim and crown may both 30 consist of a single thickness of felt or they may be in various stratum combinations having differing proportions of the Vinyon fibers combined therein or some of such strata of the brim and crown, or the crown alone, may be entirely free 35 of the resin fibers, all as hereinafter particularly set forth.

Figures 1, 2 and 3 of the drawing show conventionally a hat in which the crown is formed of a single thickness of material while the brim is 40 formed in three strata. These figures illustrate one form in which a hat may be madeup and another form in which the hat may be constructed is shown in Figure 4.

As one example of which Figures 1 and 2 are 45 illustrative the Vinyon fibers may be incorporated in the material of the crown in any desired quantity and each of the three strata of the brim, which are designated 14 for the outside strata and 15 for the intermediate stratum, has such fibers combined therein. The Vinyon fibers in the material are designated 13 and the central or intermediate stratum preferably contains a higher percentage or a greater quantity of the resin fibers than the outer strata and than the 55 crown portion.

Preferably, the proportion of the Vinyon fibers in the outer strata 14 is approximately the same as that in the crown portion, but the proportions may be varied as desired. If a stiffer crown is desired, a larger proportion of Vinyon fiber is used in the crown felt. If a softer, less resilient crown is desired, a smaller proportion of Vinyon fiber is used in the crown felt.

In another illustrative form or embodiment, the hat construction, as illustrated in Figure 3, may have the crown portion 11 entirely free of the resin fibers and of single thickness construction, while the three stratum brim may have the resin fibers incorporated in the different strata in the same quantities or proportions as described in connection with Figures 1 and 2.

Figure 4 is illustrative of a construction wherein the crown and the brim are both of three stratum construction. In the crown, which is designated 11', the center stratum 16 contains the Vinyon fibers. In the brim, which is generally designated 12', the center stratum 17 also is the only stratum containing the Vinyon fibers, the inner and outer strata 18 of the crown and 19 of the brim being entirely free of the resin fibers. Because of this construction the center stratum provides a desirable stiffness with resiliency, while the outer strata provide a soft mellow feel and woolly texture, such as would be obtained in an all wool felt.

In making up the three stratum material for the brim construction, or for the making of a crown where a three stratum crown is to be employed, an unhardened batt is prepared containing the desired amount of Vinyon fibers and this is inserted between two unhardened batts containing smaller amounts of the resin fibers, or having no resin fibers at all therein, and the three batts are then subjected to the hardening operation so as to form a single thickness sheet of the desired thickness.

This hardening operation is one which is commonly employed in connection with the manufacture of pressed felt and since such operation is well known to those familiar with the art, it is not believed a detailed description of the same is necessary.

In making up a felt hat of crown and brim construction, after the brim has been made in the desired manner and the crown has also been made as desired, the two are sewed together and the entire hat is then put on the saddle, and then placed in a mold, where it is subjected to heat and pressure. It is in the molding operation upon the felt that the included Vinyon fibers produce the desired effect. In this operation the Vinyon fibers soften and permit the felt to conform readily to the contours of the mold.

The Vinyon fibers impart to the molded hat excellent shape retention.

We claim:

1. A hat formed of a single thickness of felt material having incorporated in the brim only, synthetic resin fibers of a copolymer of vinyl chloride and vinyl acetate.

2. A hat construction having a brim and a crown, the crown and brim being formed of a single thickness of felt material, the crown and brim each having synthetic resin fibers of a copolymer of vinyl chloride and vinyl acetate incorporated therein, the proportion of the synthetic resin fibers being greater in the brim than in the crown.

3. A hat having a brim formed of a single thickness of felt material of stratified form, there being an intermediate stratum and outer strata, the strata having synthetic resin fibers of a copolymer of vinyl chloride and vinyl acetate incorporated therein, an outer stratum containing proportionately less resin fibers than the intermediate stratum, the strata being merged one with the other whereby they are nonseparable as identifiable layers.

4. A hat of crown and brim construction, the hat being formed of single thickness felt material, the brim comprising three strata, synthetic resin fibers of a copolymer of vinyl chloride and vinyl acetate incorporated in the strata of the brim, the outer strata containing proportionately less of such fibers than the middle stratum, and the strata being merged one with the other whereby they are nonseparable as identifiable layers.

5. A hat of crown and brim construction, the hat being formed of single thickness felt material, the brim comprising three strata, synthetic resin fibers of a copolymer of vinyl chloride and vinyl acetate incorporated in the strata of the brim and in the crown, the synthetic resin fibers in the middle stratum of the brim being in greater proportion than in the outer strata of the brim and in the crown, and the strata being merged one with the other whereby they are nonseparable as identifiable layers.

6. A felt hat construction as described in claim 5 wherein the proportion of the synthetic resin fibers in the outer strata of the brim and in the crown is approximately the same.

7. A hat of crown and brim construction formed of a single thickness of felt material, in which both the crown and the brim consist of three strata, the center stratum only of both the crown and the brim containing synthetic resin fibers of a copolymer of vinyl chloride and vinyl acetate, and the strata being merged one with the other whereby they are nonseparable as identifiable layers.

8. A hat construction consisting of crown and brim parts formed of a single thickness of true felt material, synthetic resin fibers of a copolymer of vinyl chloride and vinyl acetate incorporated in one of said parts, and the said fibers in the said one part being concentrated in a stratum lying between and spaced from the surfaces of the said one part, said stratum being a non-separable but identifiable portion of the single thickness of true felt.
